FIG. 4 Among J. Preston
By Daniel Breed Atty

UNITED STATES PATENT OFFICE.

ALMON J. PRESTON, OF EAST GUILFORD, NEW YORK.

IMPROVEMENT IN CAR-COUPINGS.

Specification forming part of Letters Patent No. **154,903**, dated September 8, 1874; application filed June 18, 1874.

To all whom it may concern:

Be it known that I, ALMON JEROME PRESTON, of East Guilford, in the county of Chenango and State of New York, have invented certain Improvements in Car-Couplings, of which the following is a specification:

My invention consists of a novel arrangement of ball-coupling and elastic draft, which will be more fully described in the following specifications:

In the accompanying drawings, Figure 1 is a vertical and longitudinal section of a rail-track with my improvements attached thereto. Fig. 2 is a front or end view of the same. Fig. 3 is a detached view of the coupling-jaws. Fig. 4 is a link-and-ball coupling-pin to connect my coupling with the ordinary car-coupling.

A pair of clamping-jaws, A, are arranged so as to slide in a box, B. A strap of metal, H, is attached to these jaws, and passes behind the rubber cushion or spring D, so as to give an elastic draft against the stud I, projecting downward from the top of the box B. A coiled spring, C, pushes the jaws A forward, except when the coupling-pin pushes these jaws back, and thus compresses the spring in coupling the cars. A clamping-lever, E, has two arms, E', which bestride the jaws A and hold these jaws together upon the coupling-pin, as seen in Figs. 2 and 3. By pushing one end of this lever free from the pin e and letting the end drop, as shown in dotted lines, Fig. 2, the jaws

A are left to separate freely and allow the coupling-pin F to slip out, and thus uncouple the cars; but in coupling the cars it is not necessary to drop the lever E, as the jaws A are easily pushed back by the pressure of the coupling-pin, thus compressing the coiled spring C, as already explained. On the front of the car is fastened a mouth-piece, O, made flaring in order to direct the coupling-pin to the central opening in case the pin strikes at one side; and the clamping-jaws A, when closed, form a circular mouth to receive the ball of the coupling-pin, by the stroke of which the jaws are opened. Also, these jaws form a true ball-and-socket joint with the coupling-pin F, as seen in Fig. 1. On the front of the car is a removable platform, P, held in place by a lug, S, inserted into a staple on the front of the car.

Fig. 4 shows a coupling-pin with a ball at one end and a link at the other. This pin will be required in connecting the ordinary car-coupling with one of mine.

Having thus described my improvement, I claim—

The combination of the jaws A, coiled spring C, and clamping-lever E, provided with the arms E', substantially as and for the purposes set forth.

ALMON JEROME PRESTON.
